CASSETTE PACKAGING HOLDER

Larry L. Fites, Kalamazoo, and Kingsley M. Mann, Portage, Mich., and Karl A. Utrecht, Cincinnati, Ohio, assignors to The Upjohn Company, Kalamazoo, Mich.

Filed Sept. 29, 1970, Ser. No. 25,247

Term of patent 14 years

Int. Cl. D9—99

U.S. Cl. D9—187

FIG. 1 is a perspective view of a cassette holder embodying our new design;

FIG. 2 is an elevational view taken from one end thereof, the opposite end being the same as the end shown;

FIG. 3 is a top plan view thereof, the bottom being the same as the top shown; and

FIG. 4 is an end elevational view of a modified form of the cassette packaging holder shown in FIG. 1.

The broken line representation of a cassette in FIGS. 1 and 2 is for purposes of illustration only.

We claim:

The ornamental design for a cassette packaging holder, as shown and described.
